FREQUENCY MODULATION DETECTOR

Murray G. Crosby, Riverhead, and Harry Tunick,
Rye, N. Y., assignors to Radio Corporation of
America, a corporation of Delaware

Application July 31, 1940, Serial No. 348,850

4 Claims. (Cl. 250—27.1)

Our present invention relates generically to detectors of angular velocity-modulated carrier waves, and more especially to such detectors employing full wave rectification.

One of the main objects of this invention is to utilize push-pull detectors of the oppositely mistuned input type for frequency modulated waves (FM) in place of single-sided detectors of the same type, whereby full wave rectification is had with consequent balancing advantages.

Another important object of our invention is to provide an FM detector network comprising full wave rectifiers having outputs in phase opposition, while the inputs are oppositely mistuned with respect to the mean, or center, frequency of applied FM waves whereby less by-passing of carrier currents in the output circuit is required.

Still other objects of our invention are to improve the efficiency and reliability of FM detectors, and more particularly to provide such detectors in an economical manner.

The novel features which we believe to be characteristic of our invention are set forth in particularity in the appended claims; the invention itself, however, as to both its organization and method of operation will best be understood by reference to the following description taken in connection with the drawing in which we have indicated diagrammatically a circuit organization whereby our invention may be carried into effect.

In the drawing:

Fig. 1 shows one embodiment of the invention;

Fig. 2 illustrates a modification;

Fig. 3a illustrates the detector input circuit characteristic; and

Fig. 3b shows the detector output characteristic.

Referring now to the accompanying drawing, wherein like reference characters in the different figures designate similar circuit elements, there is shown in Fig. 1 the second detector of a superheterodyne receiver of FM waves. It is believed that those skilled in the art are so very well acquainted with FM receivers that it will be sufficient for the purposes of the application to disclose merely the detection network. It is to be clearly understood that phase modulated carrier waves may be received by the present detection system. The generic term "angular velocity-modulated carrier waves" is used to cover both types of modulation. Let it be assumed, then, that the resonant circuit 1 is the output network of the usual amplitude limiter of the receiver. Briefly, the limiter is a stage of intermediate frequency (I. F.) amplification which follows one

or more normal I. F. amplifiers, and acts to eliminate from the FM signals fed to the detector any amplitude variation. It may be assumed that the FM band is of the order of 42 to 50 megacycles (mc.), and that the first detector would reduce the carrier frequency to an I. F. value of the order of 2.1 mc. The maximum frequency deviation of the carrier may be narrow or wide, and may be chosen from a range of 30 to 200 kilocycles (kc.).

It will be understood that the symbol f_c designates the mean, or center, frequency of the FM signals. At I. F. the value of f_c would be 2.1 mc. Hence, circuit 1 is fixedly tuned to the center frequency f_c . The I. F. energy of variable frequency and constant amplitude at network 1 is applied to a pair of full wave rectifiers having independent input circuits, and a common output circuit. The rectifiers may comprise a pair of twin-triode tubes 2 and 3. Tube 2 has two pair of triodes in its envelope, the cathodes being connected in common to ground. The control grids 4 and 5 are connected to opposite ends of the input coil 6, and shunt condenser 7 tunes the coil to a frequency $f_c + a$. The incremental frequency a may be any value, but will usually depend on the maximum permissible frequency swing of the carrier. The plates of the tube are connected in common, or cophasally, to one end of the primary winding 8 of the audio transformer 9.

The mid-point of coil 6 is connected to ground through the grid leak resistor 10. Hence, the tube 2 and its associated circuit functions as a full wave detector of the grid leak type. The usual I. F. by-pass condenser 10' across the leak resistor 10 may be minimized since the input circuit 6—7 is connected to grids 4 and 5 in push-pull arrangement, and, therefore, balances out the I. F. component. Similarly, tube 3 has its cathodes connected in common to ground. The control grids 11 and 12 are connected to the opposite ends of input coil 13, and the latter is tuned to a frequency $f_c - a$ by condenser 14. The plates to frequency $f_c - a$ by condenser 14. The plates of tube 3 are cophasally connected to the opposite end of winding 8. The mid-point of winding 8 is connected to a source of positive voltage. The grid leak resistor 15 is connected to ground from the mid-point of coil 13. Here, again, the tube 3 functions as a full wave detector of the grid leak type. The usual by-pass condenser 15' across resistor 15 may be minimized, in view of the balancing out of the I. F. component in the circuit 13—14. This type of detection is especially advantageous when it is desired to use a low I. F.

which it is difficult to filter out of the following audio network.

The primary circuit 1 is magnetically coupled, as at M and M₁, to each of 6-7 and 13-14, respectively. The secondary winding of the transformer 9 may be connected to any desired type of audio frequency network, assuming of course that the modulating signal used to swing the carrier frequency is music or speech. Where phase modulated carrier signals are received, a correction filter 16 should be connected to the winding 9. Such a filter would have a characteristic, shown in the rectangle 16, which relates "output" and "frequency" in an inverse sense. The switches 16' could be used to cut out filter 16 when receiving FM waves.

The arrangement of Fig. 2 differs from that of Fig. 1 in that full wave diode rectifiers are employed in place of full wave triode detectors. Thus, the double diode 20, which may be of the 6H6 type, has its anodes connected to the opposite ends of input coil 6, while the cathodes are connected back to the mid-point of coil 6 through lead 24 and resistor element 21. In the same way, the anodes of double diode tube 22 are connected to the opposite ends of coil 13, while the cathodes of the tube 22 are connected back to the mid-point of coil 13 through resistor 23 and lead 24. The cathode end of resistor 23 is at ground potential.

Each of resistors 21 and 23 acts as the output load of its respective full wave rectifier; that is, tubes 20 and 22 respectively. Since the input circuit of each double diode is in push-pull relation to the diodes, the I. F. component across each load resistor is balanced out. Hence, the usual I. F. by-pass condensers across each load resistor 21 and 23 may readily be minimized. Here, as in Fig. 1, the input network 1 is reactively coupled to each of the circuits 6-7 and 13-14. Across resistors 21 and 23 in series will be developed both direct current and audio frequency voltages which will correspond in amplitude to the frequency swings of the modulated carrier.

In Fig. 3a there is shown the input circuit characteristic of the detectors of both Figs. 1 and 2. It will be recognized that the curve whose mid-frequency is $f_c - a$ is the resonance curve of network 13-14. The curve whose mid-frequency is $f_c + a$ is the resonance curve of network 6-7. The mean, or center, frequency f_c is located midway of the upper and lower resonant frequencies.

In Fig. 3b there is shown the detector output characteristic of each of the detector arrangements of Figs. 1 and 2. It will be observed that rectified voltage varies somewhat in an S shaped curve with respect to the center frequency (f_c). In other words, the detected voltage developed across the winding 8 of transformer 9 in Fig. 1 varies with frequency deviation as shown in Fig. 3b. Again, in the case of Fig. 2 the detected voltage across resistors 21 and 23 varies with frequency deviation as shown in Fig. 3b.

It will be seen that the two pair of full wave rectifiers in each of Figs. 1 and 2 provide differential rectifier networks. Although each full wave rectifier has its own output load circuit, and the rectified voltage developed in each rectifier is present across the respective loads, the two output voltages are of opposite polarities and therefore tend to cancel each other. The final, or resultant, output voltage present across the output circuit depends upon the relative magnitudes of the individual voltages across each half of winding 8 in Fig. 1, or across resistors 21

and 23 in Fig. 2. If the two rectified voltages produced by each full wave rectifier are equal, the net voltage is zero. Since the two tuned circuits 6-7 and 13-14 are peaked to different frequencies, their response to the frequencies present in the primary circuit will be different. Fig. 3a graphically shows the response of the two input circuits in terms of frequency. It is only at the mean frequency (f_c) that the response of both circuits is the same. At all other frequencies the response of one input circuit is different from that of the other input circuit with the result that the magnitude of signal voltage fed to the two full wave rectifiers for rectification depends upon the response of the input circuit to the frequency of the signal voltage. The typical S characteristic shown in Fig. 3b is secured by simply combining the voltages developing across the output impedance of each of the full wave rectifiers. For example, at the mean frequency (f_c) the response of each of the input circuits is the same, and the voltages developed across the output load impedances are of equal magnitude but of opposite polarity, and hence the net output voltage is zero. Now, as the carrier frequency varies from the value f_c due to the modulating signal, one or the other of the output impedances will develop the greater voltage depending upon the direction of the frequency deviation of the carrier frequency. In other words, the arrangements shown in Figs. 1 and 2 provide rectifying means whereby it is possible to convert frequency variations into audio voltages of different amplitudes. In order to secure a linear output, the frequency excursions of the carrier should not exceed the linear portion of the discriminator characteristic.

In Fig. 2 it has been indicated that the audio voltage developed across the output load 21-23 is utilized for further amplification in an audio frequency amplifier network. However, the direct current voltage developed between the upper end of resistor 21 and ground may be employed for automatic frequency control (AFC), as is well known to those skilled in the art. That is to say, the direct current voltage can be used to vary the usual frequency control tube provided in association with the local oscillator tank circuit so as to correct for frequency shift of the local oscillator. This may be done because a shift in the local oscillator frequency results in a shift of the I. F. value, and the latter shift may readily be translated into a correction bias which will adjust the oscillator tank circuit frequency in a sense to maintain the desired I. F. value.

It will now be seen that there has been provided by the present invention FM wave detectors which generally comprise a pair of full wave rectifiers having their output circuits arranged in common in phase opposition, whereas the input circuits of the full wave rectifiers are oppositely mistuned from the operating mean frequency of the FM signals by equal frequency magnitudes. The result of the full wave rectification in each half of the detector circuit is to improve balancing with respect to the I. F. component. An advantage of such improved balancing resides in the fact that the usual I. F. by-pass condensers across the output load resistors in Fig. 2, or across the grid leak resistors in Fig. 1, may be reduced in magnitude thereby providing distortion-free detection.

While we have indicated and described a system for carrying our invention into effect, it will be apparent to one skilled in the art that our in-

vention is by no means limited to the particular organization shown and described, but that many modifications may be made without departing from the scope of our invention, as set forth in the appended claims.

What is claimed is:

1. In a frequency modulated carrier wave detection system, a pair of full wave rectifiers, said rectifiers having independent wave input circuits, means for applying to said independent input circuits frequency modulated waves, said independent circuits being oppositely mistuned by equal frequency magnitudes with respect to the mean frequency of said waves, and means for connecting the output circuits of said full wave rectifiers in phase opposition to provide a modulation voltage output circuit. 15

2. In combination with a source of frequency modulated carrier waves, a pair of rectifier devices, a resonant input circuit coupled to said source and tuned to a frequency which differs by a predetermined frequency value from the center frequency of said frequency modulated waves, said rectifier devices having input electrodes connected to said input circuit in phase opposing relation, a second pair of rectifier devices, a second input circuit coupled to said source and being tuned to a frequency which differs from said center frequency by said frequency magnitude but in the opposite sense, said second pair of devices having input electrodes connected in phase opposition to said second input circuit, and an output im- 30

pedance connecting output electrodes of said two pairs of devices in phase opposition.

3. In an angular velocity modulated carrier wave detection system, a pair of full wave rectifiers, each of said rectifiers having its own wave input circuit, means for applying to said input circuits angular velocity modulated waves, said input circuits being oppositely mistuned by equal frequency magnitudes with respect to the center frequency of said waves, and means for connecting the output circuits of said full wave rectifiers in opposition to provide a modulation voltage output circuit. 10

4. In combination with a source of angular velocity modulated carrier waves, a pair of detectors, a resonant input circuit coupled to said source and tuned to a frequency which differs by a predetermined frequency value from the center frequency of said modulated waves, said detectors each having input electrodes connected to said input circuit in phase opposing relation, a second pair of detectors, a second input circuit coupled to said source and being tuned to a frequency which differs from said center frequency by said frequency magnitude but in the opposite sense, said second pair of detectors having input electrodes connected in phase opposition to said second input circuit, and an output impedance connecting output electrodes of said two pairs of detectors in phase opposition. 20 25 30
